UNITED STATES PATENT OFFICE.

ARNOLD PFAU, OF MILWAUKEE, WISCONSIN, ASSIGNOR TO ALLIS-CHALMERS MANUFACTURING COMPANY, OF MILWAUKEE, WISCONSIN, A CORPORATION OF DELAWARE.

WATER-WHEEL BUCKET.

Application filed September 14, 1922. Serial No. 588,165.

This invention relates generally to improvements in the construction of buckets for water wheels of the impulse type, that is, of the type in which one or more jets of water are delivered against successive buckets of an annular series attached to the periphery of a rotor.

An object of the invention is to provide an impulse water wheel bucket which is simple in construction and efficient in operation.

It has heretofore been customary to form impulse water wheel buckets with laterally adjacent ovoid pockets, and to attach these pockets to a supporting disk or ring by means of one or more shanks. In wheels of relatively small diameter, it is difficult to secure sufficiently strong attachments for the individual buckets, because of the relatively small shanks, the size of which is limited by the number of buckets and by the diameter of the supporting element. In wheels of this type operable under high heads, the buckets must be of sufficient strength to resist the enormous pressures to which they are subjected during operation. Due to the relatively high speed of operation of wheels of this type, the buckets must be securely attached to the supporting element and such attachment should preferably consist of as few individual parts as possible, in order to avoid detachment of the buckets. It is also preferable in the construction of impulse water wheels, to have the successive buckets of identical construction so that they may be readily interchanged or replaced.

The present invention contemplates the provision of a relatively strong bucket structure provided with exceedingly simple means for attaching the same to a support. Buckets embodying the present invention may be readily utilized in wheels of relatively small diameter without danger of detachment of the buckets during the operation of the machine. In accordance with the present invention each bucket is provided with a stiffening rib at the rear of each of the ovoid pockets, and a single shank is employed to support the pockets from the supporting shaft. In order to enable utilization of the buckets in a wheel of small diameter without danger of detachment of the buckets, the buckets of the present invention are arranged in pairs having a com-

mon shank. The present invention also provides simple and efficient means for relieving the buckets and the retaining bolts from centrifugal force. These and other advantages of the improved bucket will be apparent from the following description.

A clear conception of an embodiment of the invention and of the operation of a water wheel embodying buckets constructed in accordance therewith, may be had by referring to the drawing accompanying and forming a part of this specification in which like reference characters designate the same or similar parts in the several views.

Fig. 1 is a fragmentary sectional view of an impulse water wheel, the section being taken in the plane of the buckets and of the driving jet.

Fig. 2 is a fragmentary radial section through the wheel disclosed in Fig. 1, the section being taken between two of the buckets having a common supporting shank.

The water wheel comprises generally a main supporting shaft 6 which may be disposed with its axis either horizontal or vertical, a flange 7 formed integral with the shaft 6, a bucket supporting ring 5 rigidly attached to the flange 7, and a series of buckets 2 each comprising a pair of complementary ovoid pockets and supporting lugs or shanks 4 firmly attached to the supporting ring 5. The attachment of the ring 5 to the flange 6 is effected by means of an annular series of bolts 8 which extend through aligned openings in the ring 5 and flange 7. The adjacent bucket shanks 4 have radial abutting end faces and attachment of the buckets to the ring 5 is effected by means of oppositely directed interlocking lateral projections 10, 9 formed on the ring 5 and bucket shanks 4 respectively, and by means of bolts 11, 12 extending through aligned openings in the ring 5 and lugs 4. The bucket shanks 4 thus form a continuous disk having a continuous annular projection 9 surrounded by the lateral ring projection 10. With this association of elements, the fastening bolts 11, 12 are entirely relieved from shearing action which may be induced by centrifugal force or inertia.

Each of the buckets 2 comprises a pair of complementary ovoid pockets each of which has a strengthening rib 3 formed integral with and extending longitudinally along the

rear of the pocket. The ovoid pockets and the strengthening ribs 3 at the rear thereof are formed integral with the supporting shank 4, and the buckets are arranged in sets of two or more so that one supporting shank 4 is formed integral with each set of buckets. Each of the buckets 2 is further provided with a transverse stiffening rib 13 connecting the stiffening ribs 3 and formed integral with the ovoid pockets and with the ribs 3, the rib 13 also functioning to prevent over-speeding of the wheel.

During the operation of the water wheel, one or more jets 14 of water ordinarily traveling at high velocity are delivered against the buckets 2 in tangential directions as indicated in Fig. 1. The impact of the jets 14 causes the water wheel to rotate in a clockwise direction as viewed in Fig. 1, at relatively high speed and to impart rotation to the main shaft 6.

It will be obvious that the jets 14 directed against the buckets 2 at high velocity produce enormous impact. The enormous forces thus produced are however effectively resisted by the provision of a stiffening rib 3 for each of the ovoid pockets, by the further provision of the transverse rib 13 connecting the stiffening ribs 3, and by the solid union of the shanks 4 with the ring 5. The interlocking projections 9, 10 of the shanks 4, and ring 5 respectively, effectively resist centrifugal forces induced by rotation of the wheel at high speed, and the bolts 11, 12 prevent relative lateral displacement of the projections 9, 10. It will be obvious that due to the actual contact of the successive bucket shanks 4 along radial end faces, the friction between the projections 9, 10 produced by centrifugal force, will effectively prevent tendency toward circumferential displacement of the buckets, thereby entirely relieving the bolts 11, 12 from shearing forces. While the supporting shanks 4 are formed in sections, the supporting ring 5 is formed in one piece and is attached to a continuous annular flange 7 formed integral with the shaft 6, thereby providing a rigid union between the segmental bucket supporting shanks 4 and the shaft 6. It will also be obvious that by utilizing a single lug or shank 4 for two or more buckets 2, the available area for at-

tachment of the shanks 2 to the ring 5 is increased to a maximum without necessitating replacement of a great number of buckets in case one of the buckets breaks. By attaching the shanks 4 to one side of a single supporting ring 5 only, the buckets 2 may be quickly attached or removed. The entire structure is of exceedingly simple construction and provides a water wheel capable of effectively resisting the various forces to which it may be subjected during normal operation.

It should be understood that it is not desired to limit the invention to the exact details of construction and of operation herein shown and described, for various modifications within the scope of the claims may occur to persons skilled in the art.

It is claimed and desired to secure by Letters Patent:

1. A water wheel comprising, a pair of ovoid pockets, a strengthening rib formed integral with the rear of each of said pockets, a single shank formed integral with said pockets and with said ribs, said shank having a lateral projection provided with a surface extending perpendicular to said shank and facing said pockets, a continuous supporting ring having an oppositely extending projection provided with a surface extending perpendicular to said shank and engageable with said shank surface, and means for clamping said shank to said ring at opposite sides of said surfaces.

2. A water wheel comprising, a pair of integrally united buckets each having a pair of ovoid pockets, a strengthening rib formed integral with the rear of each of said pockets, a single shank common to both of said buckets and formed integral with said pockets and with said ribs, said shank having a lateral projection provided with a surface extending perpendicular to said shank and facing said pockets, a continuous supporting ring having an oppositely extending projection provided with a surface extending perpendicular to said shank and engageable with said shank surface, and means for clamping said shank to said ring at opposite sides of said surfaces.

In testimony whereof, the signature of the inventor is affixed hereto.

ARNOLD PFAU.
